ORNAMENTING DIE

Carl George Deubel, St. Louis, Mo., assignor to
 Progressive Service Company, St. Louis, Mo., a
 corporation of Missouri

Application November 25, 1932, Serial No. 644,232

20 Claims. (Cl. 164—29)

This invention relates to ornamenting dies, and has special reference to dies designed and adapted for use in producing ornamental outlines and configurations or ornamental cut-out openings 5 in leather and other materials used in the manufacture of shoes, although the invention may be applied to other uses.

An object of the invention is to provide an improved ornamenting die equipped with a swinging carrier for the material to be ornamented, and means for securing the material in connection with said carrier in an adjusted or gaged position whereby the carrier will place the work in a desired relationship adjacent to the ornamenting die preparatory for operation of a machine whereby the ornamenting dies are caused to produce the desired effect upon the material.

Another object of the invention is to equip an improved ornamenting die with a swinging support provided with holding means for engaging and holding the material to be ornamented in connection therewith in such a position and adjustment that when the support is moved adjacent to the die, the finished surface of the material to be ornamented is presented toward and located adjacent to the die, so that when the machine is operated to cause the die to function, the cutting or ornamenting edges of the die will operate first and directly against the finished 25 surface of the material, thus avoiding the formation of shreds and fibers that might be visible when the article is completed.

Another object of the invention is to provide an improved ornamenting die for use in producing ornamental outlines and configurations upon, or ornamental cut-outs in and through shoe uppers and other materials and articles, in combination with a swinging support adapted to engage and support the shoe uppers or other materials and 35 to place the same with the finished outer surfaces thereof toward and adjacent to the ornamenting and cutting edges of the die whereby the production and formation of objectionable fibers and shreds at or about the outlines and configurations and cut-outs is prevented.

Another object of the invention is to provide an improved ornamenting die of the type and character mentioned and designed and adapted for the purposes indicated embodying improved 50 devices for supporting and gaging the material to be ornamented by the die.

Another object of the invention is to provide an improved support and gage for the material to be ornamented with equipment for supporting 55 fitted shoe uppers and similar parts thereon or

in connection therewith, so that the outside or finished surfaces of the shoe uppers or other materials may be presented directly to the ornamenting or cutting edges of the die.

Various other objects and advantages will appear from the following description, reference being made to the annexed drawings, in which—

Fig. 1 is a plan view of my improved die having a reversed shoe upper in connection therewith ready to be swung over to present the finished outer surface of the shoe upper adjacent to the die.

Fig. 2 is a side elevation of the die, the parts being shown in the position in which they are in Fig. 1.

Fig. 3 is a plan view of the die, showing the fitted shoe upper located with the finished outer surface thereof toward or against the die.

Fig. 4 is a side elevation of the die having the parts in the position shown in Fig. 3.

Fig. 5 is an enlarged vertical cross sectional view on the line 5—5 of Fig. 3.

Fig. 6 is an enlarged sectional view of a portion of the stripper plate.

In the embodiment of the invention shown, my improved die and the swinging support for the material are mounted on a portable support 1. The entire invention is designed and constructed so that it may be easily placed in or removed from a machine, such as a die press, in order to cause the die to perform its intended function. For this purpose, the die and the combined gage and support for the material to be ornamented are mounted on the portable support 1.

A number of posts 2 are rigid with the support 1 and extend upwardly therefrom and preferably have threaded holes 3 in their upper ends.

Any appropriate form of die base 4 may be mounted on the upper ends of the posts 2 and attached thereto by removable and replaceable screws 5. The screws 5 have their heads mounted in cavities 6 in the base 4 and have their stems extending through the lower portion of said base and screwed into the threaded cavities 3. The base 4 has numerous holes 7 through which the cut-out and waste material is discharged. These holes are arranged and formed in any desired relationship to conform with the arrangement of the cutting out dies 8 which produce ornamental cut-outs in the shoe upper or other material to be ornamented by ornamental cut-outs.

The dies 8 are of the open type, so that the material cut out thereby will pass through the dies and be discharged through the holes 7.

The dies 8 are mounted rigidly in holes in a

holder plate 9 seated on the upper side of the die base 4 and detachably secured thereto by removable and replaceable fasteners 10. Thus, when any set of dies, such as the dies 8, become 5 worn or damaged, the plate 9 supporting said dies may be detached and another similar plate with a similar series of dies may be substituted therefor and fastened in connection with the die base 4.

10 As clearly shown in Fig. 1 of the drawings, the dies 8 are arranged in ornamental series. As indicated, the dies 8 form cut-outs or openings in and through the material to be ornamented.

15 A stripper plate 11 is mounted on an elastic support 12 seated on and secured to the holder plate 9 by fasteners 13. The elastic support 12 has an opening 14 through which the dies 8 project, and the stripper plate 11 has holes 15 above the respective dies 8. The upper surface of the 20 elastic support 12 is in approximate alignment with the upper ends of the cutting out dies 8, so that the upper surface of the stripper plate 11 is upwardly beyond the upper ends of said dies 8. When the die press is operated and the die is located therein, the elastic support 12 will yield and permit the dies 8 to project through the holes 15 and beyond the upper surface of the stripper plate and into and through the material in which the cut-out openings are to be 25 formed.

30 Other series of ornamenting dies 16 may be provided in connection with the stripper plate 11. As shown, these dies 16 are in rigid connection with the stripper plate 11 and are in the 35 form of teeth or projections extending upwardly from said stripper plate and of less length than the thickness of the material to be ornamented thereby, so that when the material is pressed against said dies 16, said material will not be 40 perforated but will be indented.

The dies 8 and the dies 16 may obviously be arranged in any desired relationship so as to produce any desired ornamental cut-outs and indentations in a shoe upper, for instance.

45 A pair of posts 17 are rigid with the support 1 and are separated from the series of posts 2 by an intervening space 18.

50 A plate 19 is connected with a hinge member 20 mounted on a hinge pin 21 removably supported by the posts 17 to permit removal and replacement and interchange of plates 19, as may be required by the different ornamenting dies attached to the posts 2. The plate 19 has a cut-out opening 22 as large as the area covered by the series 55 of ornamenting dies 8 and 16.

A combined clamping and gage plate 23 is connected with one edge of the plate 19 by hinges 24 and has therein an opening 25 that will register with the opening 22 in the plate 19 when the 60 plates 19 and 23 are superimposed. Gaging formations 26 and 27 are formed in connection with the plate 23, which function as visible gages to facilitate the proper centering of a fitted shoe upper, or other material to be ornamented, in 65 connection with the combined work support and gage, comprising the plates 19 and 23. As specifically shown, the gaging formation 26 is an indentation or notch in the plate 23 and the gaging formation 27 is a pointed projection in connection 70 with said plate 23. The fitted shoe upper, or other material, may be manipulated until any marks or outlines thereon are brought into proper gaging relation to the gaging parts 26 and 27 to center the shoe upper, or other material, properly 75 for operation of the die.

Clamping devices, comprising arms 28, are connected with the plate 19 by pivots 29 and have resilient clamps 30 in connection with the free ends thereof.

5 A fitted shoe upper 31 is shown mounted and gaged between the plates 19 and 23 in a relationship in which the vamp of the fitted shoe upper extends across the openings 22 and 25 and the heel portion of the shoe upper is received in the space 18. This fitted shoe upper 10 is turned inside out, as shown in the drawings, so that the outer or finished surface of the fitted shoe upper is toward and against the plate 23 and the lining of the fitted shoe upper is toward and against the plate 19.

15 The fitted shoe upper is gaged by manipulation and adjustment until it is centered properly between the plates 19 and 23. Then the arms 28 are swung to engage the clamps 30 with the marginal edges of the plates 19 and 23, thereby clamping said plates on and 20 against the interposed fitted shoe upper, or other material. The plate 19 is extended from the 25 ornamenting die, which extends upwardly. When the fitted shoe upper, or other material, is applied and gaged and clamped between the plates 19 and 23, the outer or finished surface of the fitted shoe upper, or other material, is uppermost and is plainly visible at the gaging parts 26 and 27 and through the opening 25 in the plate 23.

30 After the fitted shoe upper, or other material, has been gaged and clamped, the support therefor, comprising the plates 19 and 23, is swung over, as indicated by the arcuate line 32 (Fig. 2), to the position shown in Figs. 3, 4 and 5. As there 35 shown, the opening 25 will receive the stripper plate 11 and permit the ornamenting dies 16 to engage and contact with the outer or finished surface of the fitted shoe upper, or other material.

Then the die is placed in the die press, or other 40 machine, and said machine is operated to cause the dies 8 to cut into and through the material by cutting first into and through the outer or finished surface of the material, thus avoiding the formation of fibers around the edges of the cut-outs at the outer or exposed surface of the material. The elastic support 12 yields to permit the 45 cutting operation of the dies 8 and to permit the indenting action of the dies 16.

The cut-out pieces are discharged through the hollow dies 8 and through the holes 7. When 50 the die press is retracted, the die may be removed and the plates 19 and 23 swung backwardly to the position shown in Fig. 1. Then the clamps 30 may be disengaged to release the plate 19 and 55 permit the fitted shoe upper, or other material, to be removed, after which another fitted shoe upper, or other material, may be inserted and engaged and clamped in the support therefor and the operation repeated.

60 The gaging and ornamenting operations of this improved die may be easily and speedily performed and more artistic effects produced than by dies in which the cutting and ornamenting operations are performed otherwise than directly and initially against the outer or finished 65 surface of the material that is ornamented.

A frame 33 is rigidly attached to the posts 17 by removable and replaceable fasteners 34. Said 70 frame 33 projects beyond the posts 17 in a direction away from the ornamenting die in position to support the plate 19 in its extended adjustment, as shown in Figs. 1 and 2. Also, the frame 33 constitutes a handle whereby the ornamenting die may be placed in and removed from a die press.

75 The invention obtains all of its intended ob- 75

jects and purposes in an efficient and satisfactory manner, and may be varied widely within the scope of equivalent limits without departure from the nature and principle of the invention. I do not restrict myself in unessential particulars, but contemplate such variations as may be necessary to adapt the invention to its intended uses.

I claim:

- 10 1. A rigid vertically extended ornamenting die, a member pivotally supported at one end on a horizontal axis at a distance from said die for swinging movements to and from position across said die, and means pivotally supported at the 15 opposite end of said member for securing the material to be ornamented in connection with said member for movement thereby to position adjacent to said die.
2. A device of the character described comprising a support, a vertically extended die rigidly supported by said support, a support for the material to be ornamented, a horizontal pivot supporting one end of said second support at a distance from said die for swinging movements 25 toward and from said die, and means pivoted to the opposite end of said second support for securing the material to be ornamented in connection with said support therefor.

3. A portable support, a vertically extended ornamenting die rigid with said support, a member having one end pivotally supported by said support at a distance from said die for swinging movements about a horizontal axis to and from position across said die, an element pivotally connected with the opposite end of said member, and means for holding said member and said element in position to support between them the material to be ornamented by said die.

4. A device of the character described comprising a rigid vertically extended ornamenting die in combination with a support pivoted at one end for swinging movements toward and from said die, and means carried by said support at a distance from said pivoted end for attaching to said support a fitted shoe upper in a relationship in which said support will move the fitted shoe upper toward said die with the finished outer surface of the fitted shoe upper toward the die.

5. A device of the character described comprising a rigid vertically extended ornamenting die, a stripper plate yieldingly supported adjacent to said die, a plate pivotally supported at one end at a distance from said die for swinging movements about a horizontal axis and having an opening that is above the die when the plate is adjacent to the die, a plate hinged to the opposite end of said first plate for cooperation therewith to hold between them the material to be ornamented by said die and having an opening that is above the die when the material to be ornamented is supported adjacent to said die, and means for holding said plates in cooperative relationship to support between them the material to be ornamented.

6. A device of the character described comprising a rigid vertically extended ornamenting die, a clamp pivoted at one end for swinging movements about a horizontal axis toward and from said die, and means supported by said clamp for attaching to said clamp a fitted shoe upper for movement by said clamp to position adjacent to said die preparatory for operation of said die.

7. A device of the character described comprising a rigid vertically extended die, a clamp for a fitted shoe upper, means pivotally supporting said

clamp at one end for swinging movements about a horizontal axis toward and from said die, and means supported by said clamp for securing to said clamp a fitted shoe upper in a relationship in which the finished outer surface thereof will be presented to the die when said clamp is moved toward said die.

8. A device of the character described comprising a rigid vertically extended die, a clamp for supporting a fitted shoe upper, means pivotally supporting said clamp at one end for swinging movements about a horizontal axis toward and from said die, means supported by said clamp for securing to said clamp a fitted shoe upper in a relationship in which the finished outer surface thereof will be presented to the die when said clamp is moved toward said die, and means for supporting said clamp in extended position from said die.

9. A rigid vertically extended ornamenting die, a clamping device pivotally supported on a horizontal axis at a distance from said ornamenting die for supporting and moving the material to be ornamented to position adjacent to said die, and means for supporting said device extended from said die in position to receive the material to be ornamented.

10. A rigid vertically extended ornamenting die, a clamping device pivotally supported on a horizontal axis at a distance from said ornamenting die for supporting and moving the material to be ornamented to position adjacent to said die, means for supporting said device extended from said die in position to receive the material to be ornamented, and means for clamping to said device the material to be ornamented.

11. A device of the character described comprising a rigid vertically extended ornamenting die, a swinging clamp device movable about a horizontal axis from position adjacent to said die to position in which said support extends from said die, means for clamping the material to be ornamented in said clamping device, and a member for supporting said device extended from said die in position to receive the material to be ornamented.

12. A device of the character described comprising a portable support, a vertically extended die rigid on said support, a horizontal pivot carried by said support and separated from said die by an intervening space, a clamp member mounted at one end on said pivot for swinging movements to and from position in which said clamp member extends across said die, and means supported by said clamp member for securing a fitted shoe upper in connection with said clamp member when said clamp member is extended from said die in position in which said clamp member will place the finished outer surface of said shoe upper toward the die when said clamp member is moved to position across said die.

13. A device of the character described comprising a support, a vertically extended die rigid on said support, a clamp member pivoted at one end for swinging movements about a horizontal axis that is spaced from said die, said die, said support and said clamp member cooperating to form an intervening space, means supported by said clamp member for securing a fitted shoe upper in connection with said clamp member when said clamp member is away from said die so that said clamp member will invert said shoe upper and place the finished outer surface thereof downwardly toward the die and the heel portion of said upper in said space when said clamp member is

swung about said horizontal axis to position across said die.

14. A device of the character described comprising a support, a vertically extended die rigid on said support, a clamp device, means pivotally supporting said clamp device at one end for swinging movements about a horizontal axis from position in which said clamp device is inverted and extends away from said die to position in which 10 said clamp device extends across said die, means supported by said clamp device for securing a fitted shoe upper in connection with said clamp device in position in which the finished outer surface of the shoe upper will be placed downwardly 15 toward said die when said clamp device is moved to position to extend across said die, and means forming a space to receive the heel portion of the shoe upper at the side of said die.

15. In a shoe part ornamenting machine, the combination with ornamenting means, of means 20 for gaging either a right or left shoe part from the grain or finished face thereof movable thereafter to locate the gaged face directly over the ornamenting means.

25 16. In a shoe part ornamenting machine, the combination with ornamenting means, of means for gaging that face of the shoe part which is exposed to the operative's view movable in the machine thereafter to locate the gaged face directly over the ornamenting means.

30 17. In a shoe part ornamenting machine, the combination with ornamenting means, of a shoe part gaging mask, overlying the ornamenting means, constructed to register with some portion

of that face of the shoe upper part that is exposed to the operative's view during the gaging operation and gage said face, and reversible in the machine to position the gaged face directly over the ornamenting means.

18. In a shoe part ornamenting machine, the combination with ornamenting means, of a combined shoe part holder and gaging mask overlying the ornamenting means constructed to register with some portion of that face of the shoe upper part that is exposed to the operative's view during the gaging operation and gage said face, and reversible in the machine to position the gaged face directly over the ornamenting means.

19. In a marking machine, the combination 15 with a stripper plate provided with marking means, of a shoe part gaging mask, overlying the stripper plate, constructed to register with some portion of that face of the shoe upper part that is exposed to the operative's view during the gaging 20 operation and gage said face, and reversible in the machine to position the gaged face directly over the stripper plate.

20. In a shoe part ornamenting machine, the combination with perforating means and a stripper plate therefor provided with marking means, 25 of a shoe part gaging mask, overlying the stripper plate, constructed to register with some portion of that face of the shoe upper part that is exposed to the operative's view during the gaging 30 operation and gage said face, and reversible in the machine to position the gaged face directly over the stripper plate.

CARL GEORGE DEUBEL.
